UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

APPARATUS FOR LEVELING THE ENDS OF TOOLS.

1,129,059.

Specification of Letters Patent. Patented Feb. 23, 1915.

Application filed October 8, 1913. Serial No. 794,145.

To all whom it may concern:

Be it known that I, ARTHUR BATES, a subject of the King of England, residing at Leicester, Leicestershire, England, have invented certain Improvements in Apparatus for Leveling the Ends of Tools, of which the following description, in connection with the accompanying drawings, is a specification, like reference characters on the drawings indicating like parts in the several figures.

The present invention relates to improvements in apparatus for leveling the ends of punches and similar tools by controlling the relative movement between the latter and an abrasive member, and it is of particular advantage when a gang or plurality of punches are adapted to be operated upon simultaneously.

It has been found in the past that there is considerable difficulty when renovating a tool, as for instance a perforating punch which cuts against a hard steel surface, in finishing the tool with a level operative face and with this face in correct angular relationship to the tool shank. Moreover, it frequently happens that more of the tool is ground away by the abrasive member than is necessary. This applies particularly to the renovation of a gang or plurality of punches, drivers or similar tools that are adapted to operate simultaneously upon the work while held in rigid relationship to one another, for in this case, not only must each tool face be level and be in correct angular relationship to its shank, but all of the said faces must lie in a single plane. If the tools are renovated individually a great deal of time is required, and more time is lost in re-inserting the tools in their holding block by reason of the fact that each tool must be adjusted individually to bring it into correct position relatively to the other tools of the gang.

It is therefore an object of the present invention to provide an apparatus by the use of which one or more perforating punches or the like can be accurately leveled by means of a suitably controlled relative movement between the latter and an abrasive member with a minimum of trouble and grinding away of material.

Accordingly, a feature of this invention consists of the provision in an apparatus of the class described of an abrasive member,

a holder for maintaining a tool in contact therewith and means for giving said tool a combined reciprocatory and rotatory movement across the said member.

It is preferred to construct the apparatus so that gang punches may be operated upon without removing them from the detachable block which positions them in the machine in which they work. In the construction hereinafter described this is attained by providing the apparatus with a recess into which the shank of the ordinary detachable block may be fitted. Preferably the axis of the shank of this block is arranged parallel to or coincides with the axis about which the said relative turning movement takes place, for in this way the liability of the operative faces of the punches to be ground so that they lie in a plane which is inclined to the axis of the shank of the block is obviated, by reason of the peculiar relative movement between the abrasive member and the punches.

In the apparatus the holding device is carried by a carriage mounted for reciprocatory movement over the abrasive member and is slideable in the carriage toward and from the said member so that the ends of the punches can bear upon the latter, and the shape of the holding device is such that it can be withdrawn from the apparatus in order to facilitate the changing of the punches.

These and other features of the invention will be described in connection with an illustrative apparatus and pointed out in the appended claims.

Referring now to the accompanying drawings:—Figure 1 is a perspective of an apparatus embodying the various features of the invention, and Fig. 2 is a central transverse section of the apparatus shown in Fig. 1.

The apparatus comprises a narrow rectangular base plate 1 provided at each end with two upstanding lugs 3; and each pair of lugs supports one of two guide rods 5 arranged parallel to each other. Below the guide rods, upwardly projecting ledges 7 extend along the base plate 1, and through these ledges are threaded screws 9 which abut against an abrasive member such as an oilstone 11 resting on a level table formed upon the middle portion of the base plate. The screws 9 hold the oilstone 11 in adjust-

ed position and permit stones of various sizes to be used.

A carriage 13 is mounted for lengthwise movement on the guide rods 5, being retained thereon by bosses which are formed on the carriage and which encircle the rods. In a circular socket 15 upon the carriage 13 a bearing is formed for a vertically movable cylindrical holding device or plunger 17 which is normally kept in its lowest position in the carriage 13 by its weight. The plunger 17 is bored to receive at its lower end the tubular shank 18 of a detachable block 19 to which are secured the punches 21 which are to be operated upon. This block 19 has a flange as shown which limits its movement into the bore of the plunger 17, and one end of a spring 23 is fixed inside this plunger and the other end bears against the inner wall of the tubular shank 18 of the block 19 to prevent the latter from moving outwardly or axially of the plunger 17. This allows various sets of punches to be quickly inserted in or removed from the apparatus.

To and fro movement is given to the carriage 13 to draw the punches lengthwise of the oilstone 11, and means are herein provided to rotate the plunger 17 and consequently the punches 21 during this lengthwise movement. Accordingly, around the lower end of the plunger 17 are cut grooves in order to form gear teeth 25 which mesh with teeth 27 on a rack bar 29 arranged parallel to the rods 5 and passing through a recess in the under side of the carriage, the rack bar being supported at either end by one of the lugs 3. To prevent the carriage 13, in its reciprocatory movement, knocking violently against the lugs 3 spiral springs 31 encircle the ends of the guide rods 5 for preventing contact between the carriage and the lugs.

The punches are drawn backward and forward over the oilstone 11 by means of a handle 33 with which the upper end of the plunger 17 is provided. The stem 35 of the handle enters the bore in the plunger and is maintained therein by means of a pin 37 passing through the plunger and projecting into a groove 39 extending around the said stem. This pin-and-groove connection enables the handle to rotate freely with relation to the plunger. The weight of the plunger and the handle on it may be such as to exert the whole or a fraction of the pressure required between the punches and the oilstone.

In the operation of the machine the workman grasps the handle 33 and moves it alternately in opposite directions to reciprocate the carriage 13 on its guide rods and draw the gang of punches along the length

of the oilstone. Simultaneously with this lengthwise movement the punches are rotated about an axis normal to the surface of the oilstone by reason of the engagement of the teeth 27 on the stationary rack bar 29 with the gear teeth 25 on the lower end of the plunger 17, this plunger then rotating but without affecting the handle, which does not turn in the workman's hand by reason of the pin-and-groove connection between it and the plunger. In this way the lower ends of the punches may be accurately leveled to bring all their punching surfaces into one plane, and the liability of this plane being inclined to the axis of the shank of the detachable block is obviated.

In order to promote brevity and clearness the illustrative apparatus has been shown as adapted for use with a detachable block and hollow punches such as used in the perforating machine described in U. S. patent to Flynt No. 941,704, but it should be understood that the invention is not limited in the scope of its application to the particular apparatus shown and described.

Having thus described my invention, what I claim as new and desire to secure by Letters Patent of the United States is:

1. An apparatus of the class described, having in combination, an abrasive member, a holder for maintaining a tool in contact therewith and with the axis of said tool perpendicular to the horizontal face of said abrasive member, and means for giving said tool through said holder a combined reciprocatory and rotatory movement across said abrasive member.

2. An apparatus of the class described having, in combination, an abrasive member, a slide bearing located in proximity to said member, a carriage slideable on said bearing, a tool holder having its axis perpendicular to the operative face of said abrasive member and rotatably mounted in said carriage, and means whereby reciprocation of said carriage rotates said tool holder.

3. An apparatus of the class described, having in combination, an abrasive member, guides arranged in proximity to said member in a plane parallel to the abrasive surface thereof, a carriage reciprocable on said guides, said carriage being provided with a socket, a punch holder removably held in said socket, a stationary rack, and gearing connecting said rack with said holder.

In testimony whereof I have signed my name to this specification in the presence of two subscribing witnesses.

ARTHUR BATES.
